DESIGN FOR A GRAVE MARKER

Joseph M. Majewski, Jr., Kansas City, Mo.

Application October 1, 1937, Serial No. 71,905

Term of patent 14 years

To all whom it may concern:

Be it known that I, Joseph M. Majewski, Jr., residing at Kansas City, in the county of Jackson and State of Missouri, have invented a new, original, and ornamental Design for a Grave Marker, of which the following is a specification, reference being had to the accompanying drawing forming part thereof, in which

Figure 1 is a perspective view of a grave marker, showing my new design.

Figure 2 is a plan view of the grave marker shown in Figure 1.

Figure 3 is a front elevation of the grave marker shown in Figure 1.

The characteristic features of my design reside in a grave marker of rectangular configu-

ration having a plain central indicia-receiving panel of irregular shape, as shown, surrounded by an ornamented bevelled border; the face of the panel being sharply defined and raised above the bevelled border, and the ornamental border consisting of a wreath-like representation in relief composed of overlapping leaves pointing in opposite directions from a ribbon-bow representation positioned in the center of the side adjacent the longer side of the central panel and coming to a meeting point at the center of the opposite shorter side of the central panel as shown.

I claim:

The ornamental design for a grave marker, substantially as shown and described.

JOSEPH M. MAJEWSKI, JR.
